T. BOVEY

COMBINED INTAKE AND DISCHARGE VALVE

Filed Sept. 18, 1924

Witness:

Inventor:
Thomas Bovey.

By Thomas Bovey, Res. home, 1015 S. 10th St., Attn: Atty.

Patented July 7, 1925.

UNITED STATES PATENT OFFICE.

THOMAS BOVEY, OF CHICAGO, ILLINOIS.

COMBINED INTAKE AND DISCHARGE VALVE.

Application filed September 18, 1924. Serial No. 738,545.

To all whom it may concern:

Be it known that I, THOMAS BOVEY, a citizen of the United States, and a resident of Chicago, in the county of Cook and State of Illinois, have invented certain new and useful Improvements in a Combined Intake and Discharge Valve, of which the following is a full, clear, and exact description, such as will enable others skilled in the art to make and use the same.

My present invention relates to a valve for use in conjunction with an automobile heater, the construction of which valve is such that when the valve-plate is in normal position it permits of the continued straight-away flow of the hot gases from the exhaust manifold to the muffler, but when the valve-plate is moved to a transverse position, or at substantially a right-angle to its normal position, the valve casing will take in hot gas from the exhaust pipe and direct the same to a conduit or pipe leading to the heating radiator within the vehicle, and the same valve and casing will permit the return of the exhaust from the outlet of the heater back into the exhaust pipe. Thus there is a continuous and uninterrupted flow of the hot gas in which ever position the valve plate may be positioned.

One of the objects of my invention is to provide a valve within which there is provided a web or wall that extends from between the discharge and return stubs into the central portion of the casing where it turns downwardly to a point about mediate the ends of the valve opening or seat at the bottom of the casing so that it will be unnecessary to provide a specially constructed and positive seat for the valve when in a transverse or open position while the heater is in use.

In my prior application, filed April 5th, 1923, Serial No. 629,987 for a valve for automobile heaters, I have disclosed a valve of a type similar to the valve herein described. In said prior structure it was necessary to form or machine a seat for the edge of the valve-plate so that there would be a snug fit when the plate is moved to a transverse position in order to prevent the oppositely moving currents of hot gas interfering with each other while the heater is in use. This type of structure, is expensive from a manufacturing standpoint because it requires the use of special tools to

mill or machine out an arched seat deep in the casing. I have, in my present design of valve, provided a casing in which the web or dividing wall, which provides the inlet and return passageways, extends down to the location of the valve-spindle or stem so that it is unnecessary to mill or machine a seat for the edge of the valve-plate, as before mentioned.

It is a further object of my invention to provide a valve and valve-casing that is simple in construction and dependable in operation and which is novel in the arrangement of its parts. All the foregoing objects I prefer to accomplish in the manner substantially as hereinafter described and as more particularly pointed out in the appended claims, reference being had to the drawings accompanying this specification that form a part hereof.

In the drawings:

Figure 1 is a longitudinal side elevation of my improved valve and casing.

Figure 2 is a transverse vertical section thereof on line 2-2 of Figure 1.

Figure 3 is a central longitudinal section of the structure illustrated in Figure 1.

The drawings illustrate a typical or preferred embodiment of my invention, and in said drawings I have designated similar parts by means of the same reference characters wherever said parts occur throughout the several views. The structure preferably comprises a casting 5 that is hollow, and extending obliquely upwardly from the upper portion of the same is a discharge-stub 6, and disposed with its axis parallel with the aforesaid stub 6 is a return-stub 7 that leads into the casting for the return of the exhaust gas thereto. These stubs are adapted to receive lengths of flexible metallic hose or conduit of a length sufficient to convey the exhaust gas between valve casting and the proper ports in the radiator of the heater structure that is usually disposed on the floor of the vehicle. The radiator, the housing therefor, and the flexible pipes, may be of any suitable or well known construction and, therefore, need not be herein disclosed.

Extending in from the edge of the casting and in a plane between the parallel axes of the stubs is a wall or web 8, which, at about the central portion of the interior of the casing, turns downwardly toward the center of the bottom of the casing so as

to divide the interior of the latter into two passageways, 9 and 10, one of which (9) extends directly out of the casting and the other (10) extends parallel thereto and then turns downwardly past the adjacent end of the first passageway so that said passageways terminate alongside each other at their outer or lower ends.

The bottom of the casting or housing is provided with a longitudinally elongated opening 11, which is of substantially the same extent as the combined cross-sectional area of the two passageways and said opening 11 is substantially intersected by the adjacent end portion of the wall or web 8. The casing on its bottom is provided with a basal member 12 which may be of any suitable shape so as to be conveniently secured to the exhaust conduit or pipe that leads from the engine to the muffler. In the present instance I have shown the basal member arched or concaved upwardly so as to partially surround the cylindrical pipe or embossment and it is provided with suitable means for securing the same in place. In installing the structure just described a longitudinal elongated aperture 13 is made in the exhaust pipe 14, of sufficient width and length to accommodate the movement of the valve-plate, to be hereinafter described, so that when the arched portion of the basal member 12 is fitted upon the pipe 14 this aperture 13 will be in registry with the opening 11 formed in the casing.

35. The valve comprises an elongated plate 15 having its ends rounded into semi-circular shape so as to snugly fit the aperture 11, which is preferably correspondingly shaped in the bottom of the valve casing and said plate is mounted upon a rotatable spindle 16 that is journaled in the bearings in the opposite side walls of the casing so as to be positioned transversely of the opening at about the lower end of the dividing wall or web 8. A bell crank lever is mounted upon one of the extended ends of the spindle and has its longer arm 17 connected to one end of an operating rod that extends into the vehicle to within convenient reach of the occupants. The other or shorter arm 18 of the bell crank has a coiled contraction spring 19 connected to it, and the opposite end of said spring is secured upon the laterally bent end 20 of a rod 21 mounted in a suitable boss 22 formed on the exterior wall of the casing. This spring normally maintains the valve in a closed position upon its seat in the aperture 11 of the housing. When, however, the valve is opened by a longitudinal movement of the rod 21 the plate 15 will be moved with its spindle 16 to a position transverse of the opening or aperture 11 and with its upper portion alongside the lateral portion of the wall or web 8 while its lower portion will extend

through the aperture 13 in the exhaust pipe to interfit with the lower half thereof so as to interrupt the continuous straight-away flow of the exhaust gas. This will direct said gas up into the valve casing and into the passageway 10 from which it is discharged through the stub 6 into the pipe leading to the heater, where it circulates and returns through another pipe to the stub 7 which returns it to the exhaust pipe 14 through passageway 9 upon the opposite side of the valve plate, as indicated by arrows in Figure 3 of the drawings.

What I claim is:

1. A valve comprising a casing having an opening in its bottom, two stubs projecting from said casing, a wall dividing the interior of said casing into two passageways that communicate with said stubs, said wall extending to the opening in the bottom of said casing to divide said opening, means for securing said casing upon a chamber with the opening in registry with an opening in said chamber, and a valve plate pivotally mounted in said casing and movable into one position to close the opening therein and into a transverse position to be disposed transversely through said opening and the opening in said chamber.

2. A valve comprising a casing having an opening in its bottom, an inlet and an outlet stub communicating with the interior of said casing, a wall within said casing dividing the same into two passageways communicating with said stubs, one of said passageways leading direct to said bottom opening and the wall having a lateral portion that extends across the inner portion of said passageway and terminates adjacent said opening whereby a bend is provided in the other passageway, and a valve plate mounted in the said opening and pivoted adjacent the end of said wall.

3. A valve comprising a casing having an opening in its bottom, an inlet and an outlet stub communicating with the interior of said casing, a wall within said casing dividing the same into two passageways communicating with said stubs, one of said passageways leading direct to said bottom opening and the wall having a lateral portion that extends across the inner portion of said passageway and terminates adjacent said opening, and a valve plate mounted in the said opening and pivoted adjacent the end of said wall, in combination with the walls of a chamber having an opening therein and means for securing said valve casing to said chamber walls with the respective openings in registry, whereby said valve normally closes communication between said chamber and valve casing and is movable to a position to direct fluid from the chamber into one of the passageways and out of the other passageway into said chamber.

4. A valve comprising a casing having an opening in its bottom, lateral stubs projecting from said casing, a valve plate pivoted intermediate its ends in said opening, and a wall extending from said opening adjacent the pivot of said valve and having a lateral portion dividing the interior into two passageways leading respectively to the lateral stubs.
- 10 5. A valve comprising a casing having an elongated opening in its bottom, lateral stubs projecting from said casing, a rotatable spindle journaled in opposite walls of said casing and extended transversely across said opening intermediate the ends of the latter, an elongated valve plate fitting said opening and mounted intermediate its ends upon said spindle, and a wall extending from said opening adjacent said spindle and provided with a lateral portion dividing the interior of said casing into two passageways leading respectively to the lateral stubs.
- 15 6. A valve comprising a casing having an opening in its bottom, stubs projecting from said casing, a wall extending inwardly from the dividing line between said stubs and then turned laterally towards an intermediate portion of said opening, and a valve plate normally closing said opening and pivotally mounted adjacent the end of the lateral portion of said wall, said valve plate being movable to a position transversely across said opening and partly within said casing alongside said wall.
- 20 7. A valve comprising a casing having an
- opening in its bottom, stubs projecting from said casing, a wall extending inwardly from the dividing line between said stubs and then turned laterally to the longitudinal center of said opening whereby the interior of said casing is divided into two passageways leading from the said stubs to opposite ends of said opening, a valve plate normally closing said opening and pivotally mounted at the end of the lateral portion of said wall, and means for moving said valve plate to a position transversely through said opening and partly within said casing alongside said wall.
- 25 8. A valve comprising a casing having an opening in its bottom, stubs projecting from said casing, a wall extending inwardly from the dividing line between said stubs and terminates adjacent to the longitudinal center of said opening whereby the latter is divided into two ports and the interior of said casing is divided into two passageways leading from said stubs to the respective ports, a rotatable spindle journaled in opposite walls of said casing and contiguous to the adjacent end of said interior wall, and a valve plate mounted on said spindle and normally closing both ports and movable to a position transversely across said opening and partly within said casing alongside said interior wall.
- 30 9. A valve comprising a casing having an opening in its bottom, stubs projecting from said casing, a wall extending inwardly from the dividing line between said stubs and then turned laterally to the longitudinal center of said opening whereby the interior of said casing is divided into two passageways leading from the said stubs to opposite ends of said opening, a valve plate normally closing said opening and pivotally mounted at the end of the lateral portion of said wall, and means for moving said valve plate to a position transversely through said opening and partly within said casing alongside said wall.
- 35 10. A valve comprising a casing having an

Signed at Chicago, county of Cook and State of Illinois, this 5th day of September, 1924.

THOMAS BOVEY.
